Primary Examiner — Barbara Fox*Assistant Examiner* — Lilyana Bekic(74) *Attorney, Agent, or Firm* — King & Schickli, PLLC(57) **CLAIM**

The ornamental design for a modular respirator with visor, as shown and described.

DESCRIPTION

FIG. 1 is a front perspective view of a modular respirator with visor showing the new design;

FIG. 2 is a front view thereof;

FIG. 3 is a side view thereof;

FIG. 4 is a top view thereof;

FIG. 5 is a bottom view thereof; and,

FIG. 6 is a rear view thereof.

The broken lines in the drawings depict portions of the modular respirator with visor that form no part of the claimed design.
